UNITED STATES PATENT OFFICE.

SWITS CONDÉ, OF OSWEGO, NEW YORK.

DESIGN FOR A KNIT FABRIC.

SPECIFICATION forming part of Design No. 12,320, dated June 21, 1881.

Application filed April 26, 1881. Term of patent 14 years.

To all whom it may concern:

Be it known that I, SWITS CONDÉ, of Oswego, in the county of Oswego, in the State of New York, have invented new and useful Improvements in Design for Knitted Fabrics, of which the following, taken in connection with the accompanying drawing, is a full, clear, and exact description.

This design consists in a novel configuration of a series of mottled blocks separated from each other by horizontal and vertical mottled stripes of a different shade than the blocks, produced in knitting two or more differently-colored yarns into fabric designed for under-wear and various other purposes.

The design is fully illustrated in the annexed drawing, wherein—

a a represent the mottled blocks, which may be square or rectangular; and *b* and *b'* denote

the horizontal and vertical stripes which separate the blocks *a a* from each other, said stripes being also mottled, but of a different shade than the blocks *a*.

What I claim is—

The design for knitted fabric, consisting of a series of mottled blocks separated from each other by horizontal and vertical mottled stripes of a different shade than the blocks, substantially as described and shown.

In testimony whereof I have hereunto signed my name and affixed my seal, in the presence of two attesting witnesses, at Oswego, in the county of Oswego, in the State of New York, this 18th day of April, 1881.

SWITS CONDÉ. [L. S.]

Witnesses:

FRED. L. CONDÉ,
EDW. MAXWELL.
